[57] CLAIM

The ornamental design for a spacer guard to be mounted between the two front seat backs in an automobile, as shown and described.

DESCRIPTION

FIG. 1 is a front elevational view of a spacer guard to be mounted between the two front seat backs in an automobile, showing our new design;

FIG. 2 is a rear perspective view thereof, taken slightly from the side;

FIG. 3 is a side elevational view thereof; the side opposite that shown in FIG. 3 being the mirror image thereof; and

FIG. 4 is a top plan view thereof.

FIG.1

FIG.2

FIG. 3

FIG.4
